COMBINATION SUGAR PACKET DISPENSER, CONDIMENT AND FLOWER HOLDER

Charles A. Gant, 6319 Champlain Ave., Chicago, Ill.

Filed Mar. 6, 1961, Ser. No. 64,249

Term of patent 14 years

(Cl. D44—24)

Fig-1 -

Fig. 3.

Fig. 2.

Fig. 4.

Fig. 5.

Fig. 6.

Fig. 7.

I claim:

The ornamental design for a combination sugar packet dispenser, condiment and flower holder, as shown.
